SOLE

Lathrop Milton Witherill, Pensacola, Fla.

Application November 9, 1942, Serial No. 465,042

2 Claims. (Cl. 36—59)

This invention aims to provide a shoe sole which, as shown in the drawing, comprises a body, the outline, longitudinal section and cross section of which is a duplication of the tread surfaces of the heel, arch, ball and toes of the human foot, the body being secured, if desired, to an attaching layer simulating the human foot in outline.

The advantage of the structure is that since it is a duplication of the tread surface of the human foot, and since it is made of material having approximately the resiliency of the human foot, a firm hold on a walking surface will be secured, and slipping will be prevented.

The word "shoe" as used hereinbefore and hereinafter, is to be construed as meaning an article of footwear of any desired sort.

It is within the province of the disclosure to improve generally and to enhance the utility of devices of that type to which the present invention appertains.

With the above and other objects in view, which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

In the drawing:

Fig. 1 shows in bottom plan, a shoe sole constructed in accordance with the invention;

Fig. 2 is an elevation;

Fig. 3 is a longitudinal section;

Fig. 4 is a cross section on the line 4—4 of Fig. 1;

Fig. 5 is a cross section on the line 5—5 of Fig. 1.

In carrying out the invention there is provided a shoe sole comprising a body 1 which, in outline, longitudinal section and cross section, is a duplication of the tread surfaces of the heel, arch, ball and toes of the human foot.

The sole may include an attaching layer 2, simulating the human foot in outline, and whereunto the body 1 is firmly connected, the body and the layer preferably being formed integral. The layer 2 extends outwardly beyond all portions of the periphery of the body 1.

The material used in making the device preferably has about the same resiliency as the human foot. Rubber, a rubber composition, or the like may be employed.

Although the bare statement that the body 1 is a duplication of the tread surfaces of the heel, arch, ball and toes of the human foot, might suffice, attention is directed to the outline shown at 3 in Fig. 1, to the toes 4, to the cavity 5 which is located to the rear of the toes, to the ball 6, to the concavity 7 of the arch, and to the heel 8.

The device is simple in construction, but it affords a simple and highly useful anti-slipping shoe sole.

What is claimed is:

1. A shoe sole comprising a body which, in outline, longitudinal section and cross section, is a duplication of the tread surfaces of the heel, arch, ball and toes of the human foot.

2. A shoe sole constructed as set forth in claim 1, in combination with an attaching layer simulating the human foot in outline, and whereunto the body is firmly connected, the attaching layer extending outwardly beyond all portions of the periphery of the body.

LATHROP MILTON WITHERILL.
